UNITED STATES PATENT OFFICE.

ARTHUR TREVOR DAWSON, OF LONDON, AND JAMES HORNE, OF BARROW-IN-FURNESS, ENGLAND, ASSIGNEES TO THE VICKERS, SONS & MAXIM, LIMITED, OF SHEFFIELD, ENGLAND.

ELEVATING AND RAMMING APPARATUS FOR TURRET OR BARBETTE GUNS.

SPECIFICATION forming part of Letters Patent No. 660,418, dated October 23, 1900.

Original application filed March 26, 1900, Serial No. 10,252. Divided and this application filed August 28, 1900. Serial No. 28,347. (No model.)

To all whom it may concern:

Be it known that we, ARTHUR TREVOR DAWSON, residing at 28 Victoria street, Westminster, London, and JAMES HORNE, residing at 5 Barrow-in-Furness, in the county of Lancashire, England, citizens of England, have invented a certain new and useful Improvement in Elevating and Ramming Apparatus for Turret or Barbette Guns, (for which we 10 have applied for a patent in Great Britain, dated May 3, 1899, No. 9,335; in Japan, dated April 11, 1900; in Germany, dated March 9, 1900; in Austria, dated March 12, 1900, and in Spain, dated June 20, 1900, No. 25,689,) of 15 which the following is a specification.

This improvement was originally included in our application filed March 26, 1900, Serial No. 10,252, but has been made the subject of a fresh application, a division having been re- 20 quired by the examiner.

This invention relates to an arrangement and connection of the elevating and ramming gear of a turret or barbette gun in such a manner that when the gun is elevated or depressed 25 the rammer is always maintained in line with the bore of the gun.

The accompanying drawing is a longitudinal section of a barbette, showing in elevation a pair of guns and the elevating and ramming 30 gear arranged and connected according to this invention.

For elevating the gun toothed arcs *a*, attached to the cradle, gear with pinions on an axis *b*, which is worked by worm-gear *c* 35 from a manually-operated winch *d*, carried on a standard on the gun-platform. A toothed segment on the axis *b* is connected by gearing *e*, shaft *f*, bevel-gear *g*, vertical shaft *h*, and bevel-gear *i* to a pinion which is mounted

on a telescopic or other mechanical rammer 40 *j* and gears with a segmental rack *k*, concentric with the gun-trunnions, for the purpose of keeping the rammer in line with the axis of the gun while the gun is elevated or depressed. 45

The rammer may be worked by hand; but preferably it is worked by suitable gear from an electric or other motor *l*, driving a vertical shaft *m*, along which a bevel-pinion *n*, mounted on the rammer-frame, can slide on 50 a feather, while the shaft *m* itself has a bearing for its lower end that can turn on a horizontal shaft *o*, worked by the motor-gear.

Having thus described the nature of this invention and the best means we know for 55 carrying the same into practical effect, we claim—

In combination with the elevating-gear of a turret or barbette gun, a rammer, a pinion mounted thereon and gearing with a segmental rack concentric with the gun-trunnions, bevel-gear and shafting connecting the said pinion to a segmental rack on the axis of the elevating-gear, substantially as 60 and for the purpose set forth. 65

In testimony whereof we have hereunto set our hands in presence of the subscribing witnesses.

ARTHUR TREVOR DAWSON.
JAMES HORNE.
